United States Patent Office

Des. 179,975
Patented Apr. 2, 1957

179,975

GLOVE OR SIMILAR ARTICLE

Russell P. Kantor, New York, N. Y.

Application June 25, 1956, Serial No. 42,023

Term of patent 14 years

(Cl. D3—11)

Fig. 1 is a rear view of a glove showing my new design; and

Fig. 2 is a palm-side view thereof.

The palm portion is ventilated.

I claim:

The ornamental design for a glove or similar article, substantially as shown and described.
